WATER SKI ROPE REEL

Clarence E. Norton, 816 18th Ave. SW., Cedar Rapids, Iowa, and Thomas B. Modine, 1132 Lake Ave., Racine, Wis.

Filed Feb. 19, 1960, Ser. No. 9,933

5 Claims. (Cl. 242—86.5)

This invention relates to a water ski reel for attachment to a motor boat for the purpose of controlling the ski rope off the transom of the boat.

It is an object of this invention to provide a reel which, when attached to a motor boat or the like, will provide a mounting for a ski rope so that the rope can be reeled in and also reeled out as needed and desired by both the boat operator and the skier. In accomplishing this particular object, it is significant to recognize that the reel is provided so that it is automatically operable under the power of the boat moving in the water.

Another object of this invention is to provide an automatically operable water ski reel which readily permits the skier to position himself to either side of the fore-and-aft axis of the boat as the skier can steer to the left or right with respect to the forward direction of the boat, and which also permits the skier to move both toward and away from the boat so that he could position himself at a distance behind the boat as he so desires.

Still another object of this invention is to provide a water ski reel which enhances the safety of water skiing and which also simplifies the maneuver of the skier catching the handles at the end of the rope, and these particular, important and desirable functions are achieved through the automatic reeling in of the ski rope once the rope has been released by the skier. The importance of safer water skiing is of extreme concern to all persons interested in water skiing and likewise to improve the manner of permitting the skier to catch the handles results in providing more time for actual skiing in a given period of a day.

Still another object is to provide a convenient means for retaining the ski rope when the same is not in use.

And still a further object is to provide a ski reel which is automatically operable by the power of the boat passing through the water, but which nevertheless has provision for shielding the splashing and spraying of water into the air, and particularly toward the boat.

Other objects and advantages will become apparent upon reading the following description in conjunction with the accompanying drawings wherein:

FIG. 1 is a fragmentary side elevational view of a preferred embodiment of this invention, and with the ski reel shown in an inoperative or raised position by the dotted lines included in the view.

FIG. 2 is a rear end elevational view of the ski reel shown in FIG. 1.

The same reference numerals refer to the same parts between the two views.

The ski reel is constructed to be readily mounted on and dismounted from a transom at the rear of a motor boat or the like, and for this purpose a vertically disposed mounting bracket 10 is provided to be attached to a socket or the like, not shown, but it is understood that the bracket 10 would be disposed at the upright, rear transom of the boat. The lower end of the bracket 10 has a pivot bolt 11 extending therethrough to afford a bifurcated member 12 which extends preferably to both sides of the bracket 10, and which has a plurality of openings 13 through which mounting bolts are inserted when the member 12 is pivoted about the bolt 11 for engaging the proper bolt in one of the holes 13 with a hole in the bracket 10. Thus, it will be understood that a mounting pin or bolt passes through the hole 11 in the member 12

2

and through the bracket 10 to secure the two pieces together in a pivoted relation, and then a mounting pin or bolt passes through the selected, aligned pair of the holes 13 in the member 12 and through a hole such as the hole 14 in the lower end of the bracket 10, so that the bracket 10 and the member 12 are secured together at a desired angle, and thus the member 12 is disclosed at the desired elevation and is therefore suitable for various sizes of boats and various angles of transoms on boats so that the reel will be disposed in the water wake a suitable amount.

The drawings also show that the rear end of the member 12 supports a shaft 16, which extends between the free and bifurcated ends of the member 12. The shaft 16 in turn supports a second bracket or bifurcated member 17, which in turn supports the axle 18 of the rope reel generally designated 19. The parts mentioned are of course so arranged that the reel 19 is rotatable on the member 17 and also the member 17 is pivotal between the solid line position shown in FIG. 1 and up to a dotted line position shown in FIG. 1. It will now be mentioned that when the reel is in the lowered, solid line position, the wake of the water would be approximately as indicated by the line designated "W," so that the reel is rotated counter-clockwise as viewed in FIG. 1, while the boat moves forwardly in the water and that would be, of course, to the left as viewed in FIG. 1. Also, when the reel 19 is placed in the dotted line position shown in FIG. 1, the reel is out of the water, as indicated. Of course the reel 19 has a plurality of paddles 21 and it has a central core or spool 22 on and around which a ski tow rope 23 is wound. FIG. 1 further shows that the rope 23 engages the spool 22 at the lower half of the latter so that when the reel 19 is in the water, as mentioned, and is being rotated counter-clockwise, the rope 23 will be wound up on the spool 22.

Thus, at this time it will also be noted that the rope 23 extends from its position considerably to the rear of the boat, and it is trained over a pulley 24 which is rotatably mounted in a U-shaped swivel 26 which is secured to the bracket 10. The particular manner of mounting the member 26 on the bracket 10 is such that the U-shaped member 26 is swivelly mounted so that the skier can readily pull the rope 23 considerably to the left and to the right with respect to the fore-and-aft axis of the boat and still have the rope 23 remain taut and remain on the pulley 24 and remain operable in the manner mentioned hereinafter. Of course, the pulley 24 is rotatably mounted on the member 26 by means of the axle or trunnions 27. Thus when the reel 19 is in the water as shown in FIGS. 1 and 2, then the rope 23 will of course be wound up on the reel until the knot 28 reaches the pulley 24, at which point the rope will not be further wound up as the knot or stop 28 cannot pass beyond the pulley 24 and thus about eight or ten feet of the remaining end of the rope 23 including the handles is left floating in the water behind the boat so that the boatsman can easily guide the handles to the skier in the water so that the skier can grasp the handles and commence skiing again. Of course, when the resistance of the skier in the water is applied to the rope 23, the rope is unwound from the reel 19, as the latter slowly turns in a clockwise direction and the skier relatively moves further back with respect to the boat until the entire rope 23 is extended out of the reel 19. At that time the rope 23 also pulls the reel 19 up to the dotted line position shown in FIG. 1, so that the reel is entirely out of the water, and therefore offers no resistance to the forward motion of the boat and the skier.

It will be further noted that a stop 29 is attached by screws or the like 31 to the member 17 so that in the solid line position shown in FIG. 1, the upper edge 32

of the stop 29 abuts the lower edge of the member 12 to thereby position the reel 19 in the water as shown in solid lines in FIG. 1, and thus retain the reel 19 in the water against the resistance of the forward motion of the boat. Without such a stop it is likely that the reel 19 would not be retained in the water, but it rather would ride over the top of the water and it would not properly rotate for the purposes mentioned. Also, when the rope 23 is sufficiently taut, then the reel 19 is pulled to the dotted line position of FIG. 1, and at this time the stop 29 abuts the lower edge of the member 12 in the dotted line position shown with the stop edge 33 abutting the lower edge of the member 12, and this thus holds the reel against further clockwise rotation beyond the position shown in dotted lines in FIG. 1. In this operation of pivoting the reel 19, as described, it should be particularly noted that the reel is pivoted about an axis which is substantially directly above the axis of the reel when the latter is in the immersed position in the water as shown in solid lines in FIG. 1. Thus, the reel can be readily retained in its immersed position by the stop 29, as described, and it can also be raised to the dotted line position by the tension or force applied through the rope 23, as described.

Still further, it should be noted that a shield or shroud 34 is over the upper half of the reel 19 and provides a baffle so that the water engaged by the lower vanes 21 of the reel 19 will not be directed upwardly either toward the boat or rearwardly toward the skier, or in any other undesirable direction. Thus the shield 34 prevents the undesirable splash of the water when the reel 19 is in the water. A slot 36 is provided in the shield 34 for the passage of the rope therethrough, and also a louver 37 is provided in the top of the shield 34 to provide an opening for the escape of water from the shield 34. It has been found that without the opening 37, the water is splashed into the boat by the wheel 19. Also note that the shield 34 is mounted on the shafts 16 and 18 to be secured in position, and the front edge 38 is inclined forwardly to provide a relief from water resistance at the front area when the reel is in the water. Also, the back of the shield 34 has an opening 39 which also provides a water relief.

While a specific embodiment of this invention has been shown and described, it will be understood that certain changes in the embodiment can be effected and the invention, therefore, should be limited only by the scope of the appended claims.

What is claimed is:

1. A ski reel for attaching to a boat and connecting to the ski rope, comprising a support member attachable to the transom of said boat and extending rearwardly therefrom, a water wheel including an axle to which said rope is attached for winding and unwinding with rotation of said wheel, a connector pivotally attached on the rear end of said support member and rotatably supporting said wheel for pivotally mounting the latter behind said boat to raise and lower said wheel between a forwardly pivoted position out of the water when said rope is taut and a rearwardly pivoted position in the water when said rope is slackened, a stop interengaged between said connector and said support member for limiting rearward pivotal motion of said connector to thereby retain said connector against the rearward force of the water on said wheel, and a rope guide attached to said support member at a level above said wheel for inducing upward and forward pivotal motion to said wheel when said rope is sufficiently taut.

2. A ski reel for attaching to a boat and connecting to the ski rope, comprising a support member fixedly attachable to the transom of said boat and extending rearwardly therefrom, a water wheel including an axle to which said rope is attached for winding and unwinding

with rotation of said wheel, a connector pivotally attached on the rear end of said support member and extending therebelow and rotatably supporting said wheel on the lower end of said connector for pivotally mounting the latter behind said boat to raise and lower said wheel between a forwardly pivoted position out of the water when said rope is taut and a rearwardly pivoted position in the water when said rope is slackened, a stop interengaged between said connector and said support member for limiting rearward pivotal motion of said connector to thereby retain said connector against the rearward force of the water on said wheel, a rope guide attached to said support member forwardly and upwardly from said wheel for inducing forward pivotal motion to said wheel when said rope is sufficiently taut, and a stop on said rope for limiting the amount to be wound up on said wheel.

3. A ski reel for attaching to a boat and connecting to the ski rope for operation by the skier, comprising a support member attachable to the transom of said boat, a water wheel including paddles and an axle to which said ski rope is attached for winding up and unwinding with rotation of said water wheel, said water wheel being upwardly movably attached to said support member for positioning upwardly out of the water by the pull of said ski rope towing a skier and for positioning downwardly in the surface of the water when the pull of said ski rope is slackened, whereby said water wheel is rotated by passing through the surface of said water, stop means operatively interposed between said support member and said water wheel and being adapted for securing the latter downwardly in said water in response to slackening of said ski rope, and a rope guide attached to said support member and disposed at a level above said axle for training said ski rope thereon to thereby induce an upward pull on said water wheel under the resistance of a water skier being towed by said ski rope.

4. A water ski reel for attaching to a boat and connecting a ski rope thereto, a support member fixedly attachable to said boat for extending rearwardly thereof in a permanent position, a ski rope, a rope reel pivotally mounted on said support member for attaching said rope thereto and for pivotal movement between a raised forward position out of the water and a lowered rearward position in the water for rotation to wind up and unwind said rope, a stop interengaged between said support member and said reel for limiting pivotal movement of the latter in both said rearward position and said forward position, and a rope guide mounted on said support member in front of said reel and thereabove for directing said rope to said reel at an angle for pulling upwardly on said reel when said rope is tautly trained over said guide.

5. A water ski reel for attaching to a boat and connecting a ski rope thereto, a support member attachable to said boat for extending rearwardly thereof, a ski rope including a stop thereon, a rope reel pivotally mounted on said support member for attaching said rope thereto and for pivotal movement between a raised forward position out of the water and a lowered rearward position in the water for rotation to wind up and unwind said rope, a stop disposed in abutting relation between said support member and said reel for limiting the latter in said rearward position, a rope guide mounted on said support member in front of said reel and thereabove for directing said rope to said reel for pulling upwardly on said reel when said rope is tautly trained over said guide and for engaging said stop on said rope to limit winding up of said rope.
